C. W. HAMILTON

AIR REGISTER FOR FURNACES

Filed Jan. 23, 1926.

Patented Sept. 28, 1926.

1,601,621

UNITED STATES PATENT OFFICE.

CARL W. HAMILTON, OF NEWTON, KANSAS.

AIR REGISTER FOR FURNACES.

Application filed January 23, 1926. Serial No. 83,395.

This invention relates to improvements in air registers for furnaces and especially, furnaces of the steam boiler type, having for an object to provide a register of such construction as to insure and maintain an even and uniform supply of oxygen to the atomized oil being discharged from the furnace burner into the combustion chamber of the furnace, as well as to avoid an excess air draft through the furnace, thereby permitting a materially greater heating efficiency to be obtained from an equipped furnace, in that the absence of excess air will prevent the premature discharge of the heated combustion products from the furnace stack, allowing the same to be fully utilized.

Another and equally important object of the invention is to provide an air register of the character mentioned wherein a novel operating means is employed for collectively moving the various air regulating vanes whereby to control the supply of air to the furnace combustion chamber, insuring an even inflow of air about the complete structure and through its various discharge ports.

Other objects of the invention will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the invention.

In these drawings:

Figure 1 is a front elevation of the improved register, showing the same mounted in a furnace front, one portion of the register and the furnace front being broken away and shown in section,

Figure 2 is an enlarged vertical transverse section taken on the line 2—2 of Figure 1 looking in the direction in which the arrows point, and

Figure 3 is an enlarged fragmentary detail, partly in section, showing the mounting of the air regulating vanes adjacent their respective air discharge ports and likewise, the manner in which such vanes are selectively connected to the operating ring.

Having more particular reference to the drawings in connection with which like characters of reference will designate corresponding parts throughout, the improved air register may be stated to comprise an

annular casing of sheet metal or other suitable material generally indicated in its entirety by the numeral 1, said casing being provided with an annular air receiving and distributing chamber 2 having an air intake port or opening 3 formed in the lower portion of the inner side wall thereof while a plurality of equi-spaced air discharge ports 4 are formed in the inner wall of the annular chamber 2 and are adapted to discharge air from the chamber into the combustion chamber of an equipped furnace whereby to effect an intimate mixture of atomized oil and oxygen therewithin, thus perfecting combustion.

The casing 1 of the air register is adapted to be arranged in a furnace front, such casing, as will be noted upon reference to Figure 1, having the lateral chamber like integral extremities 5 and 5' also communicating with the annular chamber 2 of the air register, whereby preheated air will pass thereinto from a point below the furnace (the heating zone or air heating chamber described and claimed by me in a copending application for United States Letters Patent filed January 23, 1926, Serial Number 83,396) and will be fully and evenly distributed about said annular chamber 2 for discharge from such annular chamber by way of the circularly arranged and spaced air discharge ports 4 directly into the furnace combustion chamber.

In order that the various ports 4 may be adjusted so as to effectually regulate the discharge of air from the annular casing 2 into the combustion chamber of an equipped furnace, a plurality of air controlling or regulating vanes generally indicated by the numeral 6 are pivotally mounted in the opposite side walls of adjacent portions of the casing 1 through the medium of pivot pins 7, certain of the ends of which are extended beyond adjacent portions of their respective walls and provided with substantially right angularly disposed extensions 8. The free extremities of these extensions 8 are loosely received between relatively spaced pins 9 securely mounted in a pair of juxtaposed operating rings 10; the pins 9, obviously, serving as means for fixedly interconnecting said rings 10 and likewise, for effecting a means of engagement as between such rings 10 and the right angularly extended portions 8 of the aforesaid pivot pins 7.

100
105
110

To permit the transmission of rotary adjusting motion to the operating ring constituted by the juxtaposed rings 10, a plurality of radially disposed bracing arms 11 5 are fixedly connected to portions of one of said rings 10 in the manner shown in the Figures 1 and 3, one of said arms being provided with a handle extension 12 whereby an operator of the device may readily 10 engage the same and impart a rotary or rocking adjusting movement thereto for directing pivotal movement to the various air regulating vanes 6 through the medium of their right angular extensions 8 from the pivot pins 15 7. By this means of adjustment through the handle 12, it will be fully understood that the air regulating vanes 6 may be minutely and efficiently adjusted with respect to their adjacent air discharge ports 4 and by consequence, 20 the discharge of an even and uniform flow of air from the annular chamber 2 through the said ports 4 into the combustion chamber of an equipped furnace will be insured. 25 A concentrically arranged opening is formed in the outer side wall of the casing 1 and has a sleeve-like bracket 13 secured to the same as indicated at 14; a burner nozzle 15 being extended through this sleeve-like bracket 13 and opening into the combustion chamber of the equipped furnace, whereat, if desired, said nozzle may be supplied with the usual shield 16.

In operation of my improved air register, 30 the casing 1 with the integral extremities 5 and 5' is properly positioned adjacent the furnace front hereinbefore mentioned and through said extremities and the opening 3, it will be understood that a continuous and even inflow of preheated air from the heating zone beneath the furnace and into the chamber 2 will be insured. To regulate the discharge of this air circulating through the annular chamber 2 into the combustion 35 chamber of an equipped furnace, it is only necessary that the operating handle 12 be rocked in the desired direction, thereby effecting a collective pivotal movement of the various air regulating vanes 6 with respect to their particular discharge ports 4 inasmuch as the right angular extensions 8 of the pivot pins 7 are loosely connected to the operating ring 10 in the manner hereinbefore described. By proper regulation of the air 40 regulating vanes 6, it will be understood that an even and uniform supply of air from the various discharge ports 4 into the combustion chamber of an equipped furnace may be successfully maintained. If desired, each of the air regulating vanes may have offset 45 portions 17 formed upon their free extremities, whereby, when said vanes are moved to closed positions as shown in full lines in the Figure 3, an effectual closure will be had 50 whereby to absolutely prevent the passage of

any material quantity of air from the annular chamber 2 through the discharge ports 4 into the furnace combustion chamber. However, when said vanes are swung to those open positions as shown in dotted lines in the Figure 3, under influence of the operating ring 10 and the operating handle 12, the offset free portions 17 will in no way detrimentally affect the discharge of air from the ports 4. 75

Because of the mode of communication of the casing 1 with the air preheating zone of an equipped furnace construction, it will be understood that a continuous and even inflow of preheated air will be effected by way of the properly adjusted or regulated air register per se, into the combustion chamber of such furnace, this preheated air, as hereinbefore described, being evenly distributed about the annular chamber 2 of the register 80 by reason of its mode of introduction thereto both from the inlet opening 3 and from the lateral integral extremities 5 and 5'. By reason of this mode of air introduction into the chamber 2 and through the ports thereof 90 from the register per se into the combustion chamber of the equipped furnace, it will likewise be understood that an intimate admixture of atomized oil and oxygen within the combustion chamber of the furnace will 95 take place, thus, producing a maximum heating efficiency therefrom.

Manifestly, the construction shown is capable of considerable modification, and such modification as is within the scope of my 100 claims, I consider within the spirit of my invention.

I claim:

1. An air register comprising a casing having integral laterally and oppositely disposed extremities and an intermediate chamber having an additional air intake opening in one side thereof and another portion of such chamber having an air discharge port, a plurality of air regulating vanes within 105 said intermediate chamber between the laterally and oppositely disposed extremities, the intake port and the air discharge port for regulating and controlling the discharge of air through said discharge port, and means 110 engaging said vanes for effecting collective operation thereof.

2. An air register comprising a casing having a pair of integral laterally and oppositely disposed extremities upon its opposite 120 sides and an intermediate chamber having an additional air intake opening in one side thereof, and another portion of said chamber having an air discharge port therein, a plurality of air regulating vanes within 125 said intermediate chamber between the laterally and oppositely disposed extremities, the intake port and the air discharge port for regulating and controlling the discharge of air through said discharge ports, a connecting 130

ring adjacent the outer side of the intermediate chamber collectively engaging said vanes and an operating means fixed to said ring.

5 3. An air register comprising a casing having integral laterally and oppositely disposed extremities upon its opposite sides and an intermediate chamber communicating with said extremities having an additional 10 air intake opening in one side thereof below the points of communication of said extremities therewith and another portion of said chamber having an air discharge port therein, a plurality of air regulating vanes 15 mounted within said intermediate chamber between the laterally and oppositely disposed extremities, the intake port and the air discharge port for regulating and controlling the discharge of air through said 20 discharge port, and means for effecting collective movement of said vanes.

4. An air register comprising a casing having a plurality of integral laterally and oppositely disposed extremities upon the opposite sides and upper portion thereof, and an intermediate annular chamber communicating with the inner portions of said extremities having an additional air intake opening in the lower portion of one side 25 thereof and another portion of said annular chamber having an air discharge port therein, a plurality of air regulating vanes pivotally mounted within said annular chamber between the laterally disposed extremities, the intake port and the air discharge port for regulating and controlling the discharge 30 of air from said discharge port, and means exteriorly of the annular casing and connected to said vanes for effecting collective 35 operation of the same.

5. An air register comprising a casing having oppositely disposed integral lateral extremities formed on the opposite sides thereof and an intermediate annular chamber 40 communicating with the inner portions of said lateral extremities, said intermediate annular chamber having an additional air intake opening in one side thereof below the point of communication of said lateral extremities therewith, and another portion of 45 said annular chamber having an air discharge port therein, a plurality of juxtaposed circularly positioned air vanes pivotally mounted within said intermediate annular chamber between the laterally 50 disposed extremities, the intake port and the air discharge port for regulating and controlling the discharge of air from said discharge port, a connecting ring adjacent the

outer side of one wall of the intermediate 60 annular chamber, and operating means fixed to said ring.

6. An air register comprising a casing having oppositely disposed integral laterally disposed extremities upon portions of the 65 opposite sides thereof and an intermediate annular chamber having an additional air intake opening in one side of the same below the points of communication of said extremities therewith and another portion of said 70 annular chamber having an air discharge port therein, a plurality of air regulating vanes positioned in circular fashion within the annular chamber between the laterally disposed extremities, the intake port and the 75 air discharge port for regulating and controlling the passage of air to and from said discharge port, pivot pins for mounting said air regulating vanes within the annular chamber, portions of said pivot pins having 80 right angular extensions thereon extended without the forward side wall of the annular chamber, a connecting ring adjacent said forward side wall of the annular chamber, the free extremities of said right angular 85 extensions having loose connection with said ring at circumferentially spaced intervals, and operating means fixed to the ring for collectively imparting pivotal movement to said air regulating vanes.

7. An air register comprising a casing 90 having integral laterally and oppositely disposed extremities and an intake chamber having an additional air intake opening in one side thereof, and another portion of such chamber having an air discharge port, 95 means for regulating and controlling communication between the laterally and oppositely disposed extremities, the intake port and the air discharge port, and other means for effecting operation of said first mentioned means.

8. An air register comprising a casing having laterally disposed air intake port and an intermediate chamber having an additional air intake opening in one side thereof 105 and another portion of such chamber having an air discharge port, a plurality of adjustable means for regulating and controlling communication between the lateral ports, the air intake opening and the air discharge 110 port, and means connected to said regulating means for effecting collective movement thereof.

In witness whereof I have hereunto set my hand.

CARL W. HAMILTON.
